UNITED STATES PATENT OFFICE

MARIE HUEBSCH, OF NEW YORK, N. Y.

HYGIENIC DEVICE

Application filed December 3, 1927. Serial No. 237,438.

This invention relates to personal hygienic devices for women and is directed to an improved simplified non-washable, pack-plug for absorbing the catamenial flow or other 5 discharges from the vagina.

One object of the invention is to provide an improved hygienic appliance of the character described which shall form a highly absorbent, sanitary pack-plug for tamponing 10 the vagina, which may be easily inserted, replaced and disposed of after use with the least inconvenience, and held comfortably in effective position without requiring pins, belts or other securing means.

Another object of the invention is to provide an improved hygienic appliance of the character described comprising few and commercially obtainable simple materials which can be readily made in size and shape to suit 20 the requirements and yet forms a small compact structure so that several appliances can be handily and inconspicuously carried about on the user's person, and shall be inexpensive to manufacture, and practical and efficient to 25 a high degree in use.

Other objects of this invention will in part be obvious and in part hereinafter pointed out.

The invention accordingly consists in the 30 features of construction, combinations of elements and arrangement of parts which will be exemplified in the construction hereinafter described and of which the scope of application will be indicated in the following claims.

In the accompanying drawing, in which is 35 shown various possible illustrative embodiments of this invention,

Fig. 1 is a front elevational view of one form of sanitary hygienic pack-plug embodying 40 the invention.

Figs. 2 and 3 are cross-sectional views taken on lines 2—2 and 3—3 respectively in Fig. 1.

Referring in detail to the drawing, 10 45 denotes an improved sanitary, hygienic, menstrual, non-washable pack-plug embodying the invention, comprising a suitably rolled filler or layer 11 of sterilized absorbent material such as cellulose formed of chemically 50 treated linen, cotton, wool, flax or wood fibre,

forming a core within a wrapper strip 12 of foraminous sheet material such as, coarsely woven surgical gauze.

The material, forming the absorbent layer and strip are readily obtainable and inexpensive and can be easily and cheaply manufactured into the improved pack-plug by relatively unskilled labor and without the use of machinery or expensive tools. 55

In the preferred form shown in the drawing, a sufficient amount of the layer material 11 is used to make a desired size and shape of pack-plug, here shown as forming an elongated frusto-conically shaped body. This is rolled within the strip 12 so as to be 60 completely wrapped therein.

One end of the body may be enclosed by a folded portion 12^a of the strip, and the opposite end of said body has a portion 12^b of said strip extending therefrom bunched 65 together or twisted into a coil for retaining the wrapper strip in position. Said twisted portion also forms an extending tail and serves as a convenient means for handling the improved pack-plug as will hereinafter 70 appear. 75

In using the pack-plug 10, it is held by tail portion 12^b and simply inserted into the cavity of the user for tamponing the vagina. When said pack-plug is in effective position 80 the walls and membranes of the cavity will close around the peripherical edge 10^a thereof of adjacent the attached end of the tail portion and prevent accidental dislodgment thereof. 85

By slightly parting the walls of the cavity at its opening the pack-plug may easily be removed on seizing the tail portion 12^b and withdrawing the pack-plug from said effective position. 90

The pack-plug may be readily disposed of in the lavatory water closet bowl since it is relatively small and will be carried away with other waste without clogging the plumbing system. 95

It is to be understood that the pack-plug may be varied in shape and size to suit the comfort and convenience of the user and the requirements to conform with the shape of the cavity in which the pack-plug is to 100

be inserted. Thus the pack-plug may be made either relatively large, medium or small and may be cylindrical, conical, frusto-conical, barrel shaped, etc.

5 It will thus be seen that there is provided a device in which the several objects of this invention are achieved and which is well adapted to meet the conditions of practical use.

10 As various possible embodiments might be made of the above invention, and as various changes might be made in the embodiment above set forth, it is to be understood that all matter herein set forth or shown in 15 the accompanying drawing is to be interpreted as illustrative and not in a limiting sense.

Having thus described my invention, I claim as new and desire to secure by Letters 20 Patent:

25 1. A sanitary hygienic pack-plug of the character described comprising a filler of absorbent material, a relatively coarse woven textile strip wrapped about said filler, portions of said strip being extended and coiled to retain the winding thereof about said filler and to form a projecting handling end.

30 2. A personal sanitary hygienic catamenial pack-plug comprising a rolled layer of absorbent cellulose material, a strip of surgical gauze wrapped tightly thereabout, an end portion of said strip being extended beyond an end of said rolled layer and twisted to secure the strip to the layer, said twisted end 35 providing a projecting means for handling the formed pack-plug.

35 3. A non-washable sanitary hygienic menstrual pack, adapted to be inserted in a cavity for tamponing the vagina comprising a body 40 formed of layer of absorbent material rolled to form a core and a wrapper strip of a relatively coarse woven surgical gauze, a portion of said gauze rolled with said layer and forming a cover for said core projecting beyond 45 said core, said portion being coiled to retain the wrapper strip on the body and to serve as a grasping means as and for the purpose described and specified.

40 4. A sanitary hygienic menstrual pack 45 adapted to be inserted in a cavity for tamponing the vagina comprising a core formed of rolled, superimposed layers of absorbent material and surgical gauze, said gauze constituting an outer wrapper for said core, a portion of said gauze projecting beyond said core and twisted to retain said core in rolled condition, and to serve as a grasping means for withdrawing said pack from the cavity.

In testimony whereof I affix my signature.
